[57] CLAIM

The ornamental design for a pole caddy, as shown and described.

DESCRIPTION

FIG. 1 is a top and front perspective view of a pole caddy showing our new design;

FIG. 2 is an enlarged front elevational view thereof;

FIG. 3 is an enlarged left side elevational view thereof, the right side being a mirror image of that shown;

FIG. 4 is an enlarged top plan view thereof; and,

FIG. 5 is an enlarged bottom plan view thereof.

The pole is shown broken-away in the views to indicated indeterminate length.
